UNITED STATES PATENT OFFICE.

PETER E. YEAGER, OF READING, PENNSYLVANIA.

AUXILIARY AIR-SUPPLY DEVICE FOR INTERNAL-COMBUSTION ENGINES.

1,332,586.

Specification of Letters Patent.

Patented Mar. 2, 1920.

Application filed September 11, 1918. Serial No. 253,580.

To all whom it may concern:

Be it known that I, PETER E. YEAGER, a citizen of the United States, residing at Reading, in the county of Berks and State of Pennsylvania, have invented certain new and useful Improvements in Auxiliary Air-Supply Devices for Internal-Combustion Engines, of which the following is a specification, reference being had to the accompanying drawings.

This invention relates to an improved auxiliary air supply device for internal combustion engines, and has for its primary object to provide a suction controlled valve mounted in the wall of the exhaust manifold which is automatically opened when the engine attains a predetermined speed to admit additional atmospheric air to the manifold and thereby lessen the richness of the combustible mixture.

It is also another important object of the invention to provide improved means for heating the auxiliary air prior to its admission to the manifold.

The invention has for a more particular object to provide a device for the above purpose embodying a mixer casing adapted to be mounted in the manifold wall and having a suction opened valve normally closing communication between the casing and the manifold, an adjustable air inlet valve plate for regulating the admission of cold atmospheric air to the casing, an air receiving conduit secured at one of its ends upon the exterior of the exhaust manifold and connected at its other end to said mixer casing to supply heated air to the latter, and means within said casing for agitating and mixing the currents of cold and heated air.

It is also a further general object of my invention to provide a device as above characterized, which is simple and durable in its construction, may be readily applied to the ordinary internal combustion engine, and is capable of manufacture at relatively small cost.

With the above and other objects in view, the invention consists in the improved construction, combination and relative arrangement of the several parts as will be herein-after more fully described, subsequently claimed and illustrated in the accompanying drawing in which similar reference

characters designate corresponding parts throughout the several views, and wherein:—

Figure 1 is an elevation showing the intake and exhaust manifolds of an internal combustion engine and illustrating the preferred embodiment of my invention applied thereto.

Fig. 2 is a side elevation of the jacket or casing 26, the mixing casing and the exhaust and intake manifolds being in section.

Fig. 3 is a section taken on the line 3—3 of Fig. 2.

Referring in detail to the drawing, 5 designates the intake manifold and 6 the exhaust manifold of an internal combustion engine. 70 The air mixer casing, designated 7, is formed at one of its ends with an exteriorly threaded stem 8, which is adapted to be tapped into the side wall of the neck leading from the carburetor to the intake manifold proper. 75 This stem at its end is formed with a valve seat 9.

The casing 7 at its opposite end is exteriorly threaded to receive a cap 10, the body wall of which is formed with air inlet 80 openings, designated 11, separated by a central, diametrically disposed web 12. The ends of this web are relatively wide, as shown at 13.

Between the body wall of the cap 10 and the end of the casing 7, an adjustable valve plate 14 is disposed, said valve plate being formed with the oppositely related, arcuate slots 15. Preferably, a packing ring or gasket 16 is interposed between the adjustable plate 14 and the end of the casing 7.

The internal diameter of the casing 7 gradually decreases from the end to which the cap 10 is applied to the stem 8 at the opposite end of said casing. A spider 17 is 95 secured within the casing 7, and in spaced relation to said spider and in the contracted end of the casing, a plate 18 is arranged and suitably secured, said plate being formed with a plurality of spaced perforations 19. 100 This plate and the spider 17 are provided with central openings, through which the valve stem 20 is freely movable. This stem at one of its ends is formed with a valve head 21, which is normally and yieldingly 105 held upon the seat 9 by means of a coil spring 22 engaged at one of its ends around a central boss exteriorly formed on the cap

10, and at its other end against the adjustable collar 23, which is threaded upon the end of the valve stem. 24 designates a lock nut for said collar.

5 Within the casing 7 and between the spider 17 and the valve plate 14, a multi-bladed agitator or mixer 25 is loosely mounted upon the valve stem 20 for free rotation and also for limited longitudinal shifting 10 movement.

Upon the outer side wall of the exhaust manifold 6, a casing or jacket 26 is engaged, the side of the jacket opposed to the manifold wall being open and having its upper 15 edge sufficiently spaced from said wall to permit air to freely pass around the manifold and into the jacket or casing. This jacket is clamped to the manifold by means of the U-bolt, shown at 27, upon the ends of 20 which suitable clamping nuts are threaded. The jacket is formed with a downwardly extending, tapering, tubular neck 28, the end of which is exteriorly threaded and is adapted to be engaged in the threaded opening 25 formed in the wall of the casing 7 between the spider 17 and the plate 18.

In the practical operation of the device, when the engine attains a predetermined speed, the suction in the intake manifold 30 pulls the valve 21 to an open position against the action of the spring 22 so that cold, atmospheric air will be drawn into the casing 7 through the openings 11 and 15. Also, heated air will be drawn through the jacket 26 around the exhaust manifold and into 35 said casing. These currents of cold and heated air are agitated and thoroughly mixed by the member 25 which is caused to rapidly rotate on the valve stem by the impact of the indrawn cold air currents against 40 the blades thereof, said member in its rotation also shifting longitudinally on the valve stem between the spider 17 and the adjustable valve plate 14. By loosening the cap 45 10, this plate can be adjusted so as to dispose a greater or less portion of the slots 15 beneath the wide ends 13 of the web 12, and thus decrease the volume of cold air entering 50 the casing 7, as may be desired. The mixture 55 of cold and heated air is finally drawn through the perforations of the plate 18 and into the intake manifold, where it mixes with the combustible charge. Thus, the air mixture is screened and the possibility of 60 particles of foreign matter entering the manifold obviated. Thus, it will be seen that as the speed of the engine increases, additional auxiliary air is admitted to the manifold and the richness of the charge 65 gradually decreased. By first heating the auxiliary air in the manner explained before admission to the manifold, the possibility of an area of relatively cold air collecting around the spark points, which would result 70 in misfiring, is obviated. The proper rel-

ative proportions of vaporized gas and air under all operating speeds of the engine is automatically accomplished by means of my invention, and the formation of carbon within the cylinder, due to an excessively rich mixture, is thus prevented.

From the foregoing description, taken in connection with the accompanying drawing, the construction, manner of operation and several advantages of the device will be clearly and fully understood. The several parts of the invention are simple and durable in their construction and can be readily assembled and applied to internal combustion engines such as are commonly employed for the propulsion of motor vehicles. The parts of the device can be also easily disassembled and access readily had thereto for the purpose of cleaning the same. I have herein shown and described what I have found to be a very practical embodiment of the device, but it is, of course, to be understood that the several elements above referred to are susceptible of considerable modifications in their form, proportion and general arrangement and I, accordingly, reserve the privilege of adopting all such legitimate changes as may be fairly embodied within the spirit and scope of the invention as claimed.

I claim:

1. An auxiliary air supply device for internal combustion engines including a casing adapted to be engaged in the wall of the intake manifold of the engine, said casing having a valve seat at one end, a cap threaded upon the other end of the casing and provided with air inlet openings, an adjustable valve plate secured in its adjusted position by the cap against the end of said casing and controlling the volume of air entering the casing, said casing having a spider, a plate fixed within the casing in spaced relation to the spider and provided with spaced perforations, a suction opened valve centrally mounted in said spider and the plate, and means yieldingly holding said valve in its closed position.

2. An auxiliary air supply device for internal combustion engines including a casing adapted to be engaged in the wall of the intake manifold of an engine, said casing having a valve seat at its inner end, a suction opened valve coacting with the seat and having a stem movable through the casing, a spring to yieldingly hold the valve upon its seat and resisting its opening action, means on the end of the casing opposite said valve for regulating the supply of atmospheric air to the casing when the valve is opened, means for supplying heated air to the casing at a point between the air inlet means and said valve, and a plate fixed within the casing between the heated air supplying means and the valve having relatively small

perforations whereby to retard the inward movement of the heated air and the atmospheric air through the valve seat.

3. An auxiliary air supply device for internal combustion engines including a casing threaded at one end for connection to the intake manifold of an engine, said end of the casing being formed with a valve seat, a suction opened valve having a stem movable through the casing, a spring yieldingly holding the valve upon its seat, means for regulating the tension of said spring, means on the opposite end of the casing for regulating the supply of atmospheric air to the casing when said valve is open, means for supplying heated air to said casing, and a multi-bladed mixing member mounted upon the valve stem within the casing and rotatable independently of the stem to mix the cold and heated atmospheric air prior to its admission to the manifold.
4. An auxiliary air supply device for internal combustion engines including a casing mounted at one end for connection to the intake manifold of an engine, said end of the casing being formed with a valve seat, a suction opened valve having a stem movable through the casing, a spring yieldingly holding the valve upon its seat, means on the opposite end of the casing for regulating the supply of atmospheric air to the casing when said valve is open, means for supplying heated air to said casing, and a multi-bladed mixing member mounted upon the valve stem within the casing and rotatable and longitudinally shiftable independently of the stem to mix the cold and heated atmospheric air prior to its admission to the manifold.
- 40 5. An auxiliary air supply device for internal combustion engines including a cas-

ing adapted at one end for insertion into the intake manifold of an engine, this end of the casing being formed with a valve seat, the opposite end of the casing being open, a suction operated valve coacting with the seat and having a stem movable through the casing, a detachable cap extending over the outer end of the casing and through which said stem passes, a spring surrounding the stem and bearing against the cap, tension adjusting nuts mounted on the stem and engaging said spring, a perforated plate disposed between said cap and the extremity of the casing, the cap having perforations coinciding with the perforations of the plate, and said plate being shiftable to adjust its perforations relative to the cap, the cap holding said plate in its adjusted positions.

6. An auxiliary air device for internal combustion engines including a casing adapted at one end for engagement in the wall of an intake manifold and provided with a suction operated inlet valve at that end, means at the opposite end of the casing for admitting atmospheric air in regulatable quantities, a plate having relatively small perforations disposed adjacent the inner end of the casing, and an air heater including a member adapted to fit over the exhaust pipe of an engine and having an air inlet opening at this end, said member being extended to form a tubular passageway entering the casing at a point between the air inlet end of the casing and said perforated plate.

In testimony whereof I hereunto affix my signature in the presence of a witness.

PETER E. YEAGER.

Witness:

M. C. LYDDANE.
